UNITED STATES PATENT OFFICE.

MATTHEW WESTRATE, OF GRAND RAPIDS, MICHIGAN.

JACKS.

Application filed April 1, 1925. Serial No. 19,843.

To all whom it may concern:

Be it known that I, MATTHEW WESTRATE, a citizen of the United States, residing at Grand Rapids, in the county of Kent and 5 State of Michigan, have invented new and useful Improvements in Jacks, of which the following is a specification.

The present invention relates to mechanical organizations and the same in connection with jacks and the like; and its object is to provide an improved mechanical organization of the character hereinafter described, and the same in connection with a lifting jack.

15 This and any other objects hereinafter appearing are attained by, and the invention finds preferable embodiment in, the mechanism hereinafter particularly described in the body of this specification and illustrated 20 by the accompanying drawings, in which:

Figure 1 is a side view of a jack;

Figure 2 is a vertical central sectional view of a portion thereof;

Figure 3 is a horizontal sectional view of 25 certain parts taken on line 3—3 of Figures 1 and 2;

Figure 4 is a horizontal sectional view of certain parts taken on line 4—4 of Figure 1;

Figure 5 is an end view of certain parts;

30 Figure 6 is a vertical sectional view of certain parts taken on line 6—6 of Figure 1; and

Figure 7 is an end view of the base of the jack.

35 In the embodiment of the invention chosen for illustration by the drawings and for detailed description in the body of this specification, a lifting jack for automobiles and the like is shown, having a base 1 and lifting means mounted thereon comprising a "lazy-tongs" structure composed of the lower pair of arms 2, 3 and upper pairs of arms 4, 5, carrying the top member 6 adapted to engage the axle or other part of the 45 automobile being raised. Each of these arms is formed of parallel members as indicated in various views, the upper ends of each pair of arms being swingably connected to the lower ends of the pair above, by bolts 50 7 passing through spacing sleeves 8, except that the upper ends of the short uppermost pair are swingably connected by a bolt 9 to the top member 6; and the arms of each pair (except the uppermost pair of short arms) 55 being swingably connected in the middle.

In the lowermost pair of arms—being

arms 2 and 3—such swingable connection is effected by bolts 10 passing through their middle portion and threaded in a block 11. This block has an axially vertical bore 20 in which a nut 12 has an axial movement limited by its radial flange 13 below the block, this nut being held non-turnably in the bore 20 by means of its spline 14 60 slideable in the keyway 15 of the block. An axially vertical screw 16 is journaled at 17 on the base 1 and is threaded in the nut 12. The lower ends of the lowermost pair 2, 3 of the arms are swingably connected by bolts 18, 19 to a pair of blocks 40, 41 respectively, 65 which are slidably movable horizontally in the guides 22, 23 of the base. These blocks 40, 41 have axially horizontal bores 24 in which nuts 25, 26 respectively have an axial movement limited by their radial flanges 27 adjacent the outer ends of the blocks, these nuts 25, 26 being held non-turnably in the 70 bores 24 by means of their said flanges being slidably guided in the guides 22, 23. A horizontally axial shaft 28 journaled at 30 in the base has right-hand and left-hand screw portions 31, 32 threaded in the nuts 25, 26 respectively. A bevel gear 33 on the shaft 28 meshes with the bevel gear 34 on the vertical screw 16, so that the rotation of 75 this shaft will rotate said screw.

In the position of the parts seen in Figure 1, the arms 2 and 4 are approximately at right angles to the other arms 3 and 5 of the respective pairs thereof, the radial flange 13 of nut 12 engaging the lower end of the block 11 and the radial flanges 27 of the pair of nuts 25, 26 engaging the outer ends of the pair of blocks 40 and 41 respectively.

90 In this position, the flange 13 is about to disengage the block 11 and the flanges 27 have just been brought into engagement with the blocks 40, 41 in the operative or raising movement of the jack, as herein-after explained.

100 When the top member 6 is in its lowest position (the lazy-tongs structure being vertically collapsed), the lower ends of the arms 2 and 3 are separated to their farthest extent, the flanges 27 being farthest away from the blocks 40 and 41 respectively, and the block 11 rests on the flange 13. The shaft 28 being now rotated to raise the top member 6 in the jack's operative movement, 105 the vertical screw 16 is rotated, thus raising the nut 12 and block 11 with it and 110

causing the top member 6 to rise. During this operation, the flanges 27 approach their blocks 40, 41 respectively. When the arms are raised to approximately the position 5 seen in Figure 1, these flanges 27 engage the blocks 40, 41 and thus continue the operative movement of the jack, but at this juncture the block 11 is carried out of engagement with the flange 13 of nut 12. It 10 will thus be seen that power to raise the jack is first applied to the block 11, and then to the blocks 40 and 41 to continue such raising movement, the power thus operating to the best advantage in either case.

15 A coiled spring 55 is desirably provided between the block 11 and flange 13 to cushion the transition of operation between block 11 and blocks 40 and 41. A crank (not shown) may be applied to the driving 20 shaft 50 connected by a universal joint 51 to the shaft 28, and this shaft 50 may be laterally moved in a vertical direction into and out of a bearing 52, on the base, opening upwardly at 53, provided for the purpose 25 of folding the parts together compactly.

It will be seen that the mechanical organization above described may be applied to other uses than to operate a lifting jack, 30 and I desire to claim the same broadly.

The invention being intended to be pointed out in the claims, is not to be limited to or by details of construction of the particular embodiment thereof illustrated by 35 the drawings or hereinbefore described.

I claim:

1. In mechanism of the character described: swingably connected arms; means 40 acting upon the ends of the arms for causing an interrelative movement thereof to a limited position; means operable in connection with the first-mentioned means, and acting upon the arms adjacent their swingable connection and in a direction transverse to the direction of the action of the first-mentioned means, for continuing said movement of the arms from said position.

2. In mechanism of the character described: swingably connected arms; threaded 50 means acting upon the ends of the arms for causing an interrelative movement thereof; threaded means operable in connection with the first-mentioned means, and acting upon the arms adjacent their swingable connection and in a direction transverse to the direction of the action of the first-mentioned means, for continuing said movement of the arms.

3. In mechanism of the character described: a base; a block; arms swingably connected to the block and having ends interrelatively movable horizontally; a nut 60 having a non-turning limited axial movement relatively to the block; a screw journaled on the base and threaded in the nut;

a block horizontally movable on the base and swingably carrying an end of an arm; a nut having a non-turning limited axial movement relatively to the last-mentioned block; a screw journaled on the base and threaded in the last-mentioned nut; means for rotating one of the screws by the rotation of the other. 70

4. In mechanism of the character described: a base; a block; arms swingably connected to the block and having ends interrelatively movable horizontally; a nut having a non-turning limited axial movement relatively to the block; a screw journaled on the base and threaded in the nut; a block horizontally movable on the base and swingably carrying an end of an arm; a nut having a non-turning limited axial movement relatively to the last-mentioned block; a screw journaled on the base and threaded in the last-mentioned nut; means for rotating one of the screws by the rotation of the other; cushioning means intermediate one of the blocks and the nut axially movable relatively thereto. 80

5. In mechanism of the character described: a base; a block; arms swingably connected to the block and having ends interrelatively movable horizontally; a nut having a non-turning limited axial movement relatively to the block; a screw journaled on the base and threaded in the nut; a pair of blocks horizontally movable on the base and swingably carrying said ends respectively; a pair of nuts having a non-turning limited axial movement relatively to the blocks respectively of said pair thereof; a shaft journaled on the base and having right-hand and left-hand screw portions threaded in the nuts respectively of said pair; means intermediate the screw and the shaft for rotating one by the rotation of the other. 90

6. In mechanism of the character described: a base; a block; arms swingably connected to the block and having ends interrelatively movable horizontally; a nut having a non-turning limited axial movement relatively to the block; a screw journaled on the base and threaded in the nut; a pair of blocks horizontally movable on the base and swingably carrying said ends respectively; a pair of nuts having a non-turning limited axial movement relatively to the blocks respectively of said pair thereof; a shaft journaled on the base and having right-hand and left-hand screw portions threaded in the nuts respectively of said pair; meshing gears on the screw and shaft respectively. 105

7. In mechanism of the character described: a base having an upwardly-open bearing; a block; arms swingably connected to the block and having ends interrelatively movable horizontally; a nut having a non- 110

turning limited axial movement relatively to the block; a screw journaled on the base and threaded in the nut; a block horizontally movable on the base and swingably carrying an end of an arm; a nut having a non-turning limited axial movement relatively to the last-mentioned block; a screw journaled on the base and threaded in the last-mentioned nut; means for rotating one of the screws by the rotation of the other; a shaft universally-jointed with the last-mentioned screw and laterally movable into and out of the open bearing.

8. In mechanism of the character described: swingably connected arms; means

acting upon the ends of the arms, and means operable in connection with said means and acting upon the arms adjacent their swingable connection and in a direction transverse to said means' direction of action, for causing an interrelative movement of the arms, said means acting in alternation with each other and one of said means continuing the movement of the arms from the position to which the other of said means had moved the same.

In testimony whereof I have hereunto set my hand at Grand Rapids, Michigan, this 28th day of March, 1925.

MATTHEW WESTRATE.
